METHOD OF ATOMIZING LIQUIDS.

1,192,645.

Specification of Letters Patent. Patented July 25, 1916.

Continuation in part of application Serial No. 229,448, filed October 21, 1904. This application filed November 13, 1913. Serial No. 800,804.

To all whom it may concern:

Be it known that I, ERNST KOERTING, a subject of the King of Prussia, residing at Villa Koerting, Pegli, Italy, have invented 5 certain new and useful Improvements in the Method of Atomizing Liquids, of which the following is a specification.

This invention relates to an improved method of atomizing liquids and has for its 10 object to attain more efficient atomization than has hitherto been usual while dispensing with the usual baffle plates against which the liquid to be atomized impinges, or the provision of means for imparting a gyratory 15 motion to the liquid as it emerges from the atomizing nozzle.

According to the present invention the liquid is supplied to a chamber and maintained under pressure therein, and a fluid or 20 gas under pressure is intimately mixed with the liquid in said chamber, the mixture being thereupon allowed to escape from the chamber through a nozzle into the atmosphere or other space at a lower pressure than 25 the pressure in said chamber. By this means the liquid is efficiently atomized as it emerges from the nozzle, the liquid tending to discharge at a certain velocity through the nozzle owing to the pressure in the chamber, while the fluid intimately mixed therewith tends to escape at a considerably greater 30 velocity according to its specific gravity, the molecules of the liquid being thereby entrained by the fluid and dispersed on emerging 35 from the orifice of the nozzle owing to the expansion of the fluid.

Any suitable fluid or gas may be employed and supplied at a pressure equal to or greater than the pressure existing in the chamber in 40 order to be intimately mixed with the liquid therein and, if desired, the fluid may consist of the gaseous vapor of the same liquid as is to be atomized.

Instead of supplying the fluid to the liquid under pressure in the chamber, the fluid 45 may be generated in the liquid in the chamber by superheating the liquid and reducing the pressure as it enters said chamber, so that the liquid will generate vapor in the chamber owing to the fall in pressure, this vapor 50 intimately mixing with the liquid.

The improved method of atomizing may be said to comprise two stages, the first stage consisting in the formation of foam either

by intimately mixing a fluid or gas under 55 pressure with the liquid while the latter is maintained under pressure in a mixing chamber, or by freeing the latent gas or vapor of the superheated liquid in the mixing chamber by reducing the pressure so that the 60 gas or vapor in a nascent state intimately mixes with the liquid and forms a foam, while the second stage consists in allowing the foam which is under pressure to expand on emerging from the mixing chamber 65 through a narrow orifice, whereby the foam bubbles are burst and particles of foam or spray formed, which spray is dispersed or atomized by the gas or vapor escaping at a high velocity. 70

In the accompanying drawings I have illustrated by way of example two types of nozzles for carrying out the method according to the present invention.

Figure 1 is a sectional view through a nozzle 75 in which the fluid is adapted to be supplied to the liquid under pressure. Fig. 2 illustrates in section a nozzle in which the fluid is generated in the liquid by reducing the pressure as the liquid enters the nozzle 80 chamber.

Referring to Fig. 1 of the drawings: 1 designates the nozzle casing to which the liquid to be atomized is supplied through a connection 2 and valve 3 under pressure. 85 4 designates a tube screwed into the nozzle casing 1 and having perforations 5 at its inner end. The fluid under pressure is supplied to the tube 4 through a connection 6 and valve 7. The nozzle casing 1 terminates in a tapered discharge nozzle 8 and if desired a diaphragm 9 having a small central orifice 10 may be provided intermediate the nozzle casing 1 and the discharge nozzle 8. The liquid entering the 95 nozzle chamber 11 under pressure from the connection 2 is thus intimately mixed with the fluid emerging from the orifices 5 in the tube 4 to which the fluid is supplied, so that an intimate mixture of the liquid and 100 fluid takes place in the chamber, with the formation of foam the mixture or foam being discharged through the nozzle 8 and the liquid or foam being efficiently atomized on emerging therefrom owing to the entraining and expanding action of the fluid. It 105 will be understood that if desired, the liquid supplied to the connection 2 under pressure

may be superheated and the valve 3 adjusted so that the pressure of the liquid is reduced in passing therethrough whereby part of the vapor of the liquid present in a 5 latent and compressed state in the liquid will be set free in the nozzle chamber 11 in the form of bubbles, that is to say, the liquid will also generate its own vapor in the nozzle chamber 11 with the formation 10 of foam. The same effect will be obtained when the perforated diaphragm 9 is provided, the pressure of the mixture being reduced as it passes through the diaphragm 9, so that the liquid will generate vapor 15 with the formation of foam in the discharge nozzle 8 while at the same time the fluid mixed with the liquid will expand, thus increasing the atomizing effect on emerging 20 from the discharge nozzle 8. It will of course be understood that if the fluid is 25 capable of condensing in the liquid such, for example, as when steam is supplied to cold or warm water, the fluid must be supplied in sufficient quantity to raise the temperature of the liquid to such an extent above its boiling point at atmospheric pressure that as the mixture passes from the nozzle chamber 11 to the outlet orifice of the discharge nozzle 8, part of the fluid present in 30 a latent and compressed state in the mixture will be set free in the form of bubbles, owing to the reduction in pressure and mechanically mix with the liquid with the formation of foam as the mixture is discharged 35 from the discharge nozzle 8.

In the modification illustrated in Fig. 2 the liquid is supplied in superheated condition and under pressure by way of a connection 12 to a nozzle casing 13 through 40 a valve 14. It will be seen in this case that by regulating the valve 14 the pressure of the liquid will be reduced so that it will generate its own vapor in the form of bub-

bles with the formation of foam in the nozzle casing 13 and the intimate mixture or 45 foam formed thereby will be discharged through the nozzle orifice 15, the gas generated entraining the liquid and dispersing it as it emerges from the orifice 15 owing 50 to the expansion of the gas.

I claim:

1. The herein described method of atomizing a liquid which comprises supplying the liquid under pressure and in a superheated condition to a chamber, the pressure 55 of the liquid being reduced as it enters the chamber whereby it will generate vapor therein, the chamber and liquid supply means being so related that an intimate mixture of the liquid and its vapor occurs 60 within the chamber, and allowing the mixture to escape from the chamber into a space at a lower pressure than the pressure in said chamber, so that the liquid is atomized by the entraining and expansive action 65 of its vapor.

2. The herein described method of atomizing a liquid which comprises supplying the liquid under pressure and in a superheated condition to a chamber through a 70 constricted inlet so that the pressure of the liquid will be so reduced that it will generate vapor within the chamber and the latter being of such character that the liquid and vapor therefrom will become intimately 75 mixed therein, and allowing the mixture to escape from the chamber into a space at a lower pressure than the pressure in said chamber, so that the liquid is atomized by the entraining and expansive action of its vapor. 80

In testimony whereof I affix my signature in presence of two witnesses:

ERNST KOERTING.
